UNITED STATES PATENT OFFICE.

HENRY F. GRITZMACHER, OF KELSO TOWNSHIP, SIBLEY COUNTY, MINNESOTA.

THRASHING MACHINE.

Application filed March 5, 1923. Serial No. 622,863.

To all whom it may concern:

Be it known that I, HENRY F. GRITZMACHER, a citizen of the United States, residing at Kelso Township, in the county of 5 Sibley and State of Minnesota, have invented a new and useful Thrashing Machine, of which the following is a specification.

This invention relates to thrashers and 10 aims to provide novel means for preventing the usual air blast employed in thrashing, from passing over the grain in the grain trough.

Another object of the invention is to provide means located at the rear of the machine for directing the air blast through the riddle, the means being adjustable to regulate the blast of air.

A further object of the invention is the 20 provision of means to retain the sieve or riddle in a clean condition and free of chaff.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawings:

Figure 1 is a longitudinal sectional view through a thrasher constructed in accordance with the invention.

Figure 2 is a transverse sectional view, through the thrasher, and

Figure 3 is a fragmental sectional view disclosing the means for holding the blade in various positions of adjustment.

Referring to the drawings in detail, the reference character 5 designates the body portion of the thrasher which includes an inclined bottom member 6 formed with a trough 7 adjacent to its upper end wherein the conveyor 8 operates to remove the grain therefrom.

Supported within the body portion is the usual guide 9 that supports one extremity of the riddle 10 which may be of any desired construction and operated in any suitable manner.

Positioned above the riddle is the usual chaffer 11 formed in the usual manner and

supported by any desirable means, the 55 chaffer being preferably constructed of spaced bars.

The device forming the essence of the invention is located at the rear of the machine and is indicated at 12, the same being 60 in the form of a board provided with shafts 13 disposed at the lower ends of the sided edges thereof, the shafts being positioned in the bearing members 14 mounted in the side walls of the body portion 5. As shown, 65 one of the shafts is relatively long and accommodates the lever 15 which is secured thereto to move the member 12 to various positions of adjustment.

A bolt indicated at 16 is carried by the 70 lever 15 and moves through the curved elongated opening 17 of the keeper 18, a winged nut 19 being provided on the threaded end of the bolt to secure the lever 15 in its 75 positions of adjustment. It might be further stated that the thrasher operates in the usual manner, that is a blast of air is directed against the underside of the riddle 10 while straw containing seed is fed onto the chaffer 11 to the end that the seed is 80 released from the straw, the air blast passing through the riddle blowing the straw and chaff out through the upper end of the thrasher.

When the member 12 has been moved to 85 a position as shown by Figure 1 of the drawing, it is obvious that the air passing through the thrasher in a direction of the arrows as indicated by Figure 1 of the drawings, will strike the member 12 and 90 be directed upwardly through the riddle 10, thereby preventing the air from passing over the ends of the riddle 10 and chaffer 11.

In order that the member 12 may be operated from a point adjacent to one end 95 of the machine, an operating rod 20 is provided, which rod has pivotal connection with the member 12 at a point adjacent to one end thereof, teeth 21 being formed in the rod 20 at a point adjacent to the opposite 100 end of the rod, which teeth cooperate with the pin 22 extending laterally from one wall of the body portion 5, whereby the member 12 may be held against various positions of adjustment.

What I claim as new is:—

In a thrasher, a body portion, a riddle supported in the body portion, a board dis-

posed transversely of the body portion and arranged under the riddle, means for pivotally connecting the board to the body portion so that the upper edge of the board will contact with the riddle, and a rod having connection with the board for moving the board to various positions.

In testimony that I claim the foregoing as my own, I have hereto affixed my signature in the presence of two witnesses.

HENRY F. GRITZMACHER.
